United States Patent Office

Des. 224,955
Patented Oct. 24, 1972

224,955

STADIUM SEAT OR SIMILAR ARTICLE

Max E. Tipton, Easton, Pa., assignor to Seating
Company of America Inc., Easton, Pa.

Filed Dec. 18, 1970, Ser. No. 26,556

Term of patent 14 years

Int. Cl. D6—02

U.S. Cl. D6—197

FIG. 1

FIG. 2

FIG. 3

FIG. 4

FIG. 5

FIG. 6

FIG. 7

FIG. 8

FIG. 1 is a perspective view of the stadium seat or similar article showing my new design;

FIG. 2 is a top plan view of the seat shown in FIG. 1;

FIG. 3 is a bottom plan or underneath view of the seat illustrated in FIGS. 1 and 2;

FIG. 4 is a front view of the seat;

FIG. 5 is a rear view of the seat;

FIG. 6 is a left side view of the seat;

FIG. 7 is a right side view of the seat;

FIG. 8 is a cross-sectional view of the seat taken along line 8-8 of FIG. 2.

I claim:

The ornamental design for a stadium seat or similar article, as shown and described.
